EQUIPMENT RACK

Henry Dreyfuss, South Pasadena, Calif., assignor to
Minneapolis-Honeywell Regulator Company, Minne-
apolis, Minn., a corporation of Delaware

Filed Jan. 24, 1961, Ser. No. 63,669

Term of patent 14 years

(Cl. D33—19)

FIG. 1

FIG. 2

FIG. 1 is a front perspective view of an equipment rack showing my new design.

FIG. 2 is an enlarged cross-sectional view thereof, taken on line 2—2 in FIG. 1 with a portion thereof being broken away for convenience of illustration.

The other side of the rack is substantially the same as the side shown. The top and back of the rack are conventional. The dominant features of my design reside in the portion shown in full lines.

I claim:

The ornamental design for an equipment rack, substantially as shown and described.
